[57] **CLAIM**

The ornamental design for a vehicle lamp, as shown and described.

DESCRIPTION

FIG. 1 is a top plan view of a vehicle lamp, showing a typical embodiment of my new design;

FIG. 2 is a front elevational view of the embodiment shown in FIG. 1, the rear view being a mirror image thereof;

FIG. 3 is a right side elevational view of the embodiment shown in FIG. 1, the left side view being a mirror image thereof;

FIG. 4 is a bottom plan view of the embodiment shown in FIG. 1; and,

FIG. 5 is a top, front and right side perspective view of the embodiment shown in FIG. 1.
